UNITED STATES PATENT OFFICE.

LIZZIE S. STEWART, OF NEW CASTLE, PENNSYLVANIA.

DESIGN FOR A LADY'S HAT.

SPECIFICATION forming part of Design No. 18,908, dated February 5, 1889.

Application filed November 26, 1888. Serial No. 291,913. Term of patent 3½ years.

To all whom it may concern:

Be it known that I, LIZZIE S. STEWART, a citizen of the United States of America, residing at New Castle, in the county of Lawrence and State of Pennsylvania, have invented a certain new and useful Design for a Hat for Ladies' Wear, of which the following is a specification, reference being had therein to the accompanying drawings.

10 My invention relates to a new design for a hat for ladies' wear, the leading feature of the design being the representation of an artist's palette in the contour of any portion of the brim of the hat, the upper and lower edges of 15 the body of the hat being peculiarly curved, as shown, and hereinafter fully described.

In the accompanying drawings, Figure 1 is a plan view of the hat. Fig. 2 is a left side 20 perspective view of the hat, and Fig. 3 is a right side elevation of the hat.

25 In my new design the lower edge of the body A of the hat is abruptly curved downward, as shown at *a a'* on the left side and at *b b'* on the right side. One portion at least of the brim B is shaped to represent an art-

ist's palette, having the curved recess *c* and the thumb-hole *d*. The upper edges of the body of the hat are slightly convexed at the sides, as shown, from *f* to *h* and from *f'* to *h'*, and are concaved at the front and back, as 30 shown, from *f* to *f'* and from *h* to *h'*. The hat being placed in position for the front and back portions of the brim to rest on a horizontal plane, the front portion, *A'*, of the body A is nearly vertical, being very slightly inclined backward at the top, while the back portion of the body is very perceptibly inclined forward.

What I claim as new, and desire to secure by Letters Patent, is—

40 The new design for a hat, consisting of the shape and configuration herein shown and described.

In testimony whereof I affix my signature in presence of two witnesses.

LIZZIE S. STEWART.
